UNITED STATES PATENT OFFICE.

GEORGE E. DOW, OF SAN FRANCISCO, CALIFORNIA.

STEAM-ACTUATED VALVE.

SPECIFICATION forming part of Letters Patent No. 309,610, dated December 23, 1884.

Application filed December 14, 1883. (No model.)

To all whom it may concern:

Be it known that I, GEORGE E. Dow, of the city and county of San Francisco, and State of California, have invented an Improvement 5 in Steam-Actuated Valves for Direct-Acting Steam-Engines; and I hereby declare the following to be a full, clear, and exact description thereof.

My invention relates to certain improvements in direct-acting steam-engines.

It consists of a main cylinder with a piston reciprocating therein, a piston-rod connecting the piston with the exterior apparatus to be moved thereby, a combination of main and auxiliary valves and corresponding ports, and an auxiliary piston by which both valves are moved, the stem of said valve being connected by a mechanism outside of the cylinders with the main piston-rod, so that a positive 15 motion is imparted to the valves, and a bracket and guide for the sliding sleeve, through which motion is communicated to the supplemental or steam-chest piston, with its main and auxiliary valves, from the main piston-rod, together with certain details of construction, which will be more fully explained by reference to the accompanying drawings, in which—

Figure 1 is a longitudinal vertical section 30 of my engine through xx , Fig. 3. Fig. 2 is an enlarged vertical section of the valve-chamber, supplemental piston, main and auxiliary valves, and steam-ports. Fig. 3 is a transverse section taken through yy , Figs. 1 and 2. Fig. 4 is a transverse section through zz , Fig. 35 1. Fig. 5 is a plan of the valve-faces, showing the ports. Fig. 6 is a bottom view of the auxiliary valve in perspective. Fig. 7 is a top view of same in perspective.

This invention is more particularly applicable to an engine for which Letters Patent 40 were issued to me January 10, 1882, and numbered 252,084. In this patent I have stated that any mechanism may be employed for operating the valves which will give a positive connection with the main piston or rod to impart motion in the proper direction and admit of the valves completing the latter half of the stroke by steam-pressure independent of 45 the movement of the main piston, and I have 50

shown a mechanism by which this may be accomplished.

In my present invention I have shown another mechanism for accomplishing the same result, with certain improvements which I 55 will proceed to describe.

A is the main cylinder of my engine. B is the piston, and C is the piston-rod, which passes through a stuffing-box, D, in one cylinder-head, and may pass through another 60 stuffing-box in a pump-cylinder head connecting with the pump-piston, so as to drive it directly when the engine is used in connection with a pump.

E is the steam-chest and valve-chamber, 65 within which the main and auxiliary valves F and G are moved over their respective ports.

H is the supplemental or auxiliary piston, the ends of which fit and move in cylindrical chambers, and the central portion is recessed 70 to receive the valves, the ends of the recess acting to move the valves when they come in contact with them while moving in either direction, as shown in my former patent. In the present case the auxiliary valve G is made 75 of such a length that its ends never uncover the steam-passages I I', which lead to the ends of the supplemental piston-chambers; but it has ports J J made vertically through it, through which steam is admitted to the passages while 80 said ports are passing over them. As the auxiliary valve fits closely the recess in the supplemental piston by which it is driven, it is moved the full length of the stroke of the latter, while the main valve, being shorter, is not moved 85 until after the auxiliary valve-port J has commenced to open, as shown in my former patent. When this port does open, steam is admitted to the chamber behind the supplemental piston to complete its stroke and fully 90 open the main valve. It also carries the auxiliary valve over so far that the port J is carried beyond the passage I, and it is again closed so that no more steam will be admitted. The passages I I' are so located where they 95 open into the supplemental cylinders that they offer sufficient cushion on the exhaust-steam to prevent their striking the cylinder-heads, as shown in my former patent.

The effect of my improved valve is to cut off 100

the steam from the acting side of the supplemental piston when the valves have moved far enough to fully open the main ports. This makes the exhaust-cushion still more effective 5 than before, as the steam is cut off from acting upon the opposite end of the supplemental piston.

K is the stem or rod of the supplemental piston which drives the valves. This rod extends out through a stuffing-box above and parallel with the main piston-rod, and has a sleeve, L, fitted to slide loosely upon it. A bracket, M, is bolted to or formed with the head of the supplemental cylinder, and its 15 outer end is bored out large enough to allow the sleeve to slide within it as a guide, thus giving a proper alignment of the moving ports and a steadiness to the movements, which is important.

20 N N are links, the upper ends of which are connected by pins with the opposite sides of the sleeve, and O O are short links extending from the sides of the bracket to the links N, to which they are pivoted a short distance below 25 the pins which join them to the sleeve, and they act as fulcrums about which the links N move. The lower ends of the links N are connected by links P with a block or collar, Q, which is fixed to the main piston-rod.

30 The supplemental piston-rod K is made of larger diameter outside the cylinder, and where it passes through the sleeve L, and has screw-threads cut upon this enlarged portion to receive the nuts S, which are thus adjusted to or 35 from the sleeve L. The stroke of the main piston is thus regulated so that it works at all times as closely as practicable to the cylinder-heads. The space between these nuts and the ends of the sleeve is sufficient, so that after 40 the valve has been started by the action of the lever-links N the supplemental piston will be moved the remainder of the distance of its stroke by steam admitted through the passage I independent of the movement of the main 45 piston-rod or of the connecting-levers. The links O and P allow the links N to describe an arc of a circle while following the reciprocating movement of the main piston without affecting the direct reciprocation of the sleeve L.

50 Having thus described my invention, what I claim as new, and desire to secure by Letters Patent, is—

1. In a direct-acting engine, the combination of the main and auxiliary valve-rod with 55 a sleeve sliding thereon between adjustable stops, a bracket forming a guide and support for the sleeve and rod, and the link connect-

ing the sleeve to the main piston-rod, whereby the auxiliary valve is positively operated by the engine, and the main valve by steam, substantially as herein set forth.

2. In a direct-acting engine, the combination of an auxiliary valve and a main valve, placed side by side and driven by a supplemental piston, with a piston-rod extending 65 through the cylinder-head and connected by links with the main piston-rod, adjustable nuts fitted to the supplemental piston-rod, a bracket, and a sleeve sliding upon the rod between the nuts and in the brackets, substantially as 70 and for the purpose herein set forth.

3. In a direct-acting engine, the combination of a supplemental piston for actuating both main and auxiliary valves, having a piston-rod extending outside the cylinder parallel with the main piston-rod, with two adjustable collars thereon, a sleeve sliding loosely upon said rod between the collars and moving within a bracket secured to the supplemental cylinder, and the parallel arms pivoted upon 80 each side of the sleeve and connected with the guide by fulcrum-links, the opposite ends of the arms being connected with a collar upon the main piston-rod by links, all constructed to operate substantially as herein set forth. 85

4. In a direct-acting engine, a main and auxiliary valve moving side by side upon a stationary valve-seat, a supplemental piston centrally recessed to receive and drive both main and auxiliary valves, and steam-passages leading from the auxiliary valve-seat and opening into the supplemental cylinder near the ends, said auxiliary valve being of such a length that its ends will not uncover the steam-passages, and having ports made through its 95 ends corresponding with said passages, substantially as herein described.

5. In a direct-acting engine, a main and an auxiliary valve placed side by side upon the stationary seat, having ports, as shown, and an auxiliary piston recessed or constructed to 100 drive both valves, the main valve being shorter than the auxiliary valve and having lost motion, said auxiliary valve having ports made through its ends so as to open and close the 105 steam-passages at both ends of the stroke, substantially as herein described.

In witness whereof I have hereunto set my hand.

GEO. E. DOW.
